PNEUMATIC MOTOR

Ernest W. Davis, River Forest, Ill.

Application June 15, 1945, Serial No. 599,664

4 Claims. (Cl. 121—164)

1

My invention relates generally to pneumatic motors, and more particularly to improved valve mechanisms therefor.

It is an object of my invention to provide an improved pneumatic pressure operated reciprocating motor having an improved valve mechanism.

A further object is to provide an improved balanced valve mechanism for pneumatic motors.

A further object is to provide an improved pneumatic motor which is simple in construction, reliable in operation, and which may be economically produced.

Other objects will appear from the following description, reference being had to the accompanying drawings, in which:

Fig. 1 is a central vertical sectional view of the improved lubricant compressor and pneumatic motor;

Fig. 2 is a plan view thereof;

Fig. 3 is an enlarged fragmentary sectional view of the valve mechanism, showing the positions of the valves during the downstroke of the motor piston; and

Fig. 4 is a similar view showing the positions of the valves on the upstroke of the piston.

Referring to Fig. 1, the air motor is illustrated as forming a part of a lubricant pumping mechanism customarily termed a "barrel pump," since it is adapted to remove oils and greases from barrels and drums in which the lubricants and similar products are shipped. This compressor is shown as comprising a cylinder 10 which is secured to a cover 12 of an oil drum 14, the cylinder 10 extending to the bottom of the drum and having inlet ports 16 normally closed by a foot valve 18. A piston 20 is reciprocal in the cylinder 10 and is secured to a piston rod 22. Ports 24 in the piston 20 are adapted to be closed on the upstroke of the piston by a check valve 26. The piston rod extends through a head 28 at the upper end of the barrel 10, a suitable packing gland 30 being provided. The lubricant is discharged from the barrel 10 through a pipe 32.

A motor cylinder body 34 is preferably cast integrally with pedestals 36 which have foot portions 38 clamped to the end of the barrel 10 by cap screws 40, which also secure the head 28 to the end of the barrel. A valve actuating arm 42 is clamped against a shoulder 44 formed on the piston rod 22 by a sleeve 46. Against the upper end of the latter there is clamped a piston 48, the clamping being effected by a nut 50 threaded at the upper end of the rod 22.

2

A cylinder head 52 is suitably secured to the upper end of the cylinder body casting 34, this head being provided with a passageway 54 leading from a lower valve chamber 56 to the upper end of the cylinder bore 58. The head 52 also has a passageway 60 leading from an upper valve chamber 62 to the lower end of the cylinder bore 58 through a connecting passageway 64 formed in the pump body casting 34.

10 The body casting 34 has a sidewardly extending flange portion 66 provided with a valve seat 68. A second valve seat 70 is formed between the lower valve chamber 56 and upper valve chamber 62. The upper valve chamber is threaded to receive a cylindrical bushing 72.

15 The valve assembly comprises a poppet type valve 74, for cooperation with the valve seat 68, and a second poppet valve 76, for cooperation with the valve seat 70. The valve 74 is preferably formed integrally with a valve stem 80, while the poppet valve 76 is clamped against a shoulder on the valve stem 80 by a sleeve 82 threaded on the upper end of the stem 80. A cup leather piston 84 is slidable in the bore of 20 the cylinder bushing 72 and is clamped between the sleeve 82 and nuts 86 threaded on the upper end of the valve stem 80.

25 The valve stem 80 is guided for longitudinal sliding movement in a bushed boss 88 forming part of the pump body casting 34. The lower end portion 90 of the stem 80 is of reduced diameter and has a pair of helical springs 92, 93 held thereon, the spring 92 operating to transmit force from the arm 42 to an adjustable stop 94 on the valve stem, while the spring 93 is adapted to transmit force from the arm 42 to an adjustable stop 96.

30 The operating fluid is supplied to the upper valve chamber 62 through an inlet pipe 98 provided with a shutoff valve 100.

35 In using the apparatus, the operating fluid, such as compressed air, is supplied to the upper valve chamber 62 upon opening the shutoff valve 100. Assuming that the valve assembly and piston 48 are in the positions shown in Fig. 1, the air under pressure will flow past the poppet valve 62 into the lower valve chamber 56, which is always in communication with the upper end of the cylinder 58. Thus air under pressure will be supplied to both the upper and lower ends of the cylinder 58, since it is clear that the lower end of this cylinder is at all times in communication with the upper valve chamber. However, due to the fact that the sleeve 46 is of substantial cross 40 sectional area, it will be apparent that the effec-

tive area of the upper surface of the piston 48 is much greater than that of its lower surface, and therefore the piston 48 will be moved downwardly under the influence of the difference between the forces applied to its upper and lower surfaces by the compressed air. Upon downward movement of the piston 48, lubricant contained within the lower end of the barrel 10 will flow through the ports 24 of the piston 20, 10 raising the check valve 26, and some of the lubricant will be discharged through the pipe 32, due to its displacement by the portion of the piston rod 22 which enters the barrel 10. When the piston 48 approaches the end of its down-stroke, the arm 42 will engage the spring 93 and 15 compress the latter until sufficient force is applied to the valve stem 80, 90, to snap the valve assembly from the position in which it is shown in Figs. 1 and 3 to the position in which it is shown in Fig. 4.

It will be noted that when the valve is in the position of Figs. 1 and 3, the pressure of the operating fluid is exerted on the balancing cup leather piston 84 as well as over the effective area of the valve 74. However, because the diameter of the piston 84 is greater than that of the valve 74, the operating fluid will apply a net force to the valve assembly in an upward direction to hold it in the position in which it is shown in Figs. 1 and 3. However, as the spring 93 becomes compressed 30 further toward the end of the downstroke of the motor piston 48, the force of the compressed air holding the valve assembly in its upper position will be overcome. As soon as the valve 74 leaves its seat, the pressure in the lower valve chamber 56 will drop and the force of the compressed air acting on top of the poppet valve 76, as well as the force of the compressed spring 93, will be effective rapidly to snap the valve assembly from the position shown in Figs. 1 and 3, to the position shown in Fig. 4.

When the valve mechanism is in the position shown in Fig. 4, air under pressure flows from the upper valve chamber 62 through the passageway 60, 64, to the lower end of cylinder 58. At the same time, the air in the upper end of the cylinder 58 is free to escape to the atmosphere through passageway 54, lower valve chamber 56, and through the port at the valve seat 68.

It will be noted that the effective area of the poppet valve 76 and of its seat 70 is slightly greater than that of the bore in the cylinder bushing 72, and thus the air will exert a net downward pressure on the valve assembly. This pressure will be sufficient to hold the valve assembly in the position in which it is shown in Fig. 4. Thus the motor piston 48 will be moved upwardly. During the upward stroke, the lubricant pump valve 26 closes and the lubricant above the piston 20 is discharged through the pipe 32. Also during this upward stroke, the foot valve 16 opens to admit lubricant. As the piston 48 reaches the upper end of its stroke, the spring 92 is brought into engagement with the adjustable stop 94 and compressed until it applies sufficient force to the valve stem 80, 90, to move the latter to its upper position, as shown in Figs. 1 and 3, thus completing a cycle of operation.

Due to the fact that the valves 74 and 76 are of the poppet type, and due to the use of the cup leather piston 84, the valve mechanism need not be manufactured with a very high degree of precision, and due to the successive decreases in diameter of the valve seat 70, the bore of the cylinder bushing 72, and the valve seat 68, no de-

5 tent means are required to hold the valve in its two operating positions. The dimensions of the latter parts are such that the valve will not move accidentally due to vibration, and yet sufficient force is applied to hold the valve assembly in its two operative positions so that the valve will operate with a snap action.

While I have shown and described a preferred embodiment of my invention, it will be apparent that numerous variations and modifications thereof may be made without departing from the underlying principles of the invention. I therefore desire, by the following claims, to include within the scope of the invention, all such variations and modifications by which substantially the results of my invention may be obtained through the use of substantially the same or equivalent means.

I claim:

20 1. In a fluid pressure operated motor, the combination of a motor cylinder, a motor piston reciprocable therein, a piston rod of substantial effective cross sectional area with respect to that of the piston, and valve means for controlling the supply of fluid to the opposite ends of said cylinder, said valve means comprising two chambers respectively in communication with opposite ends of said cylinder, a first valve seat providing a relatively small diameter outlet port leading from the first of said chambers to the atmosphere, a second valve seat intermediate said valve chambers, the other of said chambers having a cylindrical bore open to the atmosphere, said bore being of slightly less cross sectional area than said second valve seat, and being of substantially greater cross sectional area than said first valve seat, a valve assembly having poppet valves respectively cooperable with said valve seats and having a piston reciprocable in said cylindrical bore, and means operated by said motor piston to move said valve assembly in the direction of piston movement near the end of each stroke of the motor piston.

25 2. A valve mechanism for fluid operated reciprocating piston and cylinder type motors comprising, means forming a pair of valve chambers communicating with the opposite ends of the motor cylinder, having a first valve seat intermediate the chambers, a balancing piston having one side thereof exposed to pressure in one of said valve chambers and having its other side exposed to atmospheric pressure, a second valve seat forming an air outlet port leading from the other of said valve chambers to the atmosphere, a second valve rigidly connected to said first valve and to said piston and cooperable with said second valve seat, said valves operating in opposite directions and spaced so that when one valve is closed the other is fully opened.

30 3. In a valve mechanism for a fluid operated motor having a cylinder and a piston reciprocable therein, a valve body providing a first chamber and a second chamber, means connecting the first chamber to a source of fluid under pressure, means respectively connecting said chambers to the opposite ends of the motor cylinder, the first of said chambers having a cylindrical bore leading to the atmosphere at one side and a valve seat of greater diameter than said cylindrical bore at the other side, said second valve chamber having an outlet port of smaller diameter than said cylindrical bore leading therefrom to the atmosphere, a valve assembly comprising a piston member slidable in the cylindrical bore, a poppet valve cooperable with the valve seat, and

5

a second poppet valve for closing the outlet port, said poppet valves closing upon moving the valve assembly in opposite direction and being spaced apart so that when one valve is closed the other is opened, and means for reciprocating said valve assembly in response to movement of the motor piston near the ends of its forward and return strokes.

4. In a valve mechanism for a fluid operated motor having a cylinder and a piston reciprocable therein; a valve body providing a first chamber and a second chamber; means connecting the first chamber to a source of fluid under pressure; means respectively connecting said chambers to the opposite ends of the motor cylinder; the first of said chambers having a cylindrical bore leading to the atmosphere at one side and a valve seat of greater diameter than said cylindrical bore at

6

the other side; said second valve chamber having an outlet port of smaller diameter than said cylindrical bore leading therefrom to the atmosphere; a valve assembly comprising a piston member 10 5 15
